UNITED STATES PATENT OFFICE.

GEORGE T. O'MALEY, OF KANSAS CITY, MISSOURI.

AMUSEMENT DEVICE.

Application filed December 1, 1924. Serial No. 753,184.

To all whom it may concern:

Be it known that I, GEORGE T. O'MALEY, a citizen of the United States, residing in the city of Kansas City, county of Jackson, 5 and State of Missouri, have invented certain new and useful Improvements in an Amusement Device, of which the following is a specification.

This invention relates to improvements 10 in an amusement device or a vehicle which is so arranged as to resemble a bucking mule or horse.

The vehicle is constructed preferably 15 from a Ford car whose parts are more easily readjusted and rearranged than other makes of cars and its size of driving, reversing mechanism and braking means lend themselves admirably to sudden stopping and starting in addition to its ability to turn in 20 a relatively small space.

The vehicle is particularly adapted for 25 amusement purposes in connection with conventions, initiations, or at any time when boisterous sport is appreciated. The device is locally named "The Missouri Mule," due to the antics which it will perform when 30 operated by a person acquainted with its peculiarities. The vehicle will perform many tricks when the occupants are distributed so that the weight is properly balanced. The car may be made to rear up in front by manipulation of the reverse and 35 braking mechanism; and may also be caused to spin in a relatively small circle and to produce a bucking effect which may be accentuated by quick stopping and starting. The car may be steered with the front 40 wheels off the ground by applying the individual brakes on the rear wheels.

Fig. 1 is a side elevational view of the 45 vehicle with part of the body and frame broken away.

Fig. 2 is a plan view of the showing in 50 Fig. 1.

Fig. 3 is a front elevational view of the 55 vehicle with the upper portion of the hood removed.

Fig. 4 is a view taken along the line 4-4 in Fig. 2.

Fig. 5 is a detail along the line 5-5 in 60 Fig. 1.

Fig. 6 is an enlarged detail taken along the line 6-6 in Fig. 2.

Fig. 7 is a top plan view of the mechanism 65 shown in Fig. 6.

Fig. 8 is a fragmentary detail of the Y

member for manipulating the rear brakes.

The vehicle, or "mule" as it is called, is 60 preferably constructed as mentioned from a standard Ford touring car, using the chassis of the car and replacing pneumatic tires with semi-pneumatic or solid tires such as those shown in Fig. 1 perforated to produce a cushioning effect. To the frame shown at 1 is attached a body 2 which is 65 equipped with a front and rear seat 3 and 4. To the frame at the rear cross member 5 is attached a drag disk 6 by means of clamps 7 and a central bolt 8. When the car rears up, the rear of the frame rests 70 upon this disk and utilizes the disk as a pivoting point. The disk used is one taken from a disk gang plow of rigid steel construction able to withstand the rough usage to which it is subjected. An extra cross 75 member is placed near the center of the frame, as shown in Fig. 2 at 9. The rear spring 10 is moved forward with this cross member, as are the rear wheels 11 and axle 12 supporting the differential 13. The rear 80 end of the engine and transmission are lowered to accommodate the driving mechanism to the rearrangement of the differential. The sleeve or casing 14 surrounding the drive shaft, and the drive shaft itself 85 is shortened in order to make proper driving connection between the engine and the differential. Lugs 15 on the sleeve 14 serve as anchors for a surrounding brace 16 which surrounds and is rigidly bolted to the differential casing 13. The front axle, as shown 90 in Fig. 3, is unaltered except for the fact that the wheels are eccentrically mounted on the axle 17 by means of eccentric members 18, shown in Figs. 1 and 3. A buffer 95 spring 19 is positioned between the front axle and the frame 1 which supports the radiator at this point in order to cushion the effect of the eccentrically mounted wheels and the jolt received by the frame 100 and chassis when the body is suddenly lowered from a reared-up position. A chain 20 is also fastened between the frame and axle to reduce the sudden strain put upon the spring and shackle bolt connections when the 105 car is suddenly uplifted.

Just forward of the cross member and rear axle, and mounted beneath the frame, is a split counter shaft shown in Figs. 2 and 4 and designated as 21 and 22, respectively. 110 These counter shafts are supported from the frame by brackets designated as 23 and

by outrigger braces 24 which are attached to the frame at 25 and support the counter shafts at their outer extremities in bearings designated as 26. The counter shaft 21 has communication with the vertical hand lever 27 through a link 28 at the front end of which is affixed an L slotted member 29, a Y member 30 attached to the horizontal shaft 31 upon which the hand lever 27 is mounted. In a like manner, the counter shaft 22 is connected through a link 28, an L slotted member 29 to the opposite fork 30^a of the Y member which, as explained, is affixed to the shaft 31. Two tension springs 32, shown at 33, and attached to the links 28 and to the angle brace 33, serve to return the counter shaft to a position where the brakes are released when tension on the hand lever is removed.

As explained, the prong 30^a of the Y member has connection by means of a headed stub shaft 30^b with the L slotted member attached to the link connected to the shaft 21, while the prong 30^a of the Y member has a headed stub shaft 30^c bearing in the L slot of the member 29 which is attached to the link connected to the counter shaft 22. The mechanism and connections between the Y member and its respective prongs with the L slotted members 29, is shown in Figs. 6 and 8. Tension springs 34 maintain a continuous downward pull upon the L slotted member, causing the stub shafts 30^b and 30^c to ride in the short vertical legs of the L slots, thus making a direct connection between both of the rear brakes and the hand lever. In the event that it is desired to quickly rotate or pivot the vehicle, the brakes on either of the wheels may be disassociated from manipulation of the hand lever by pulling either of the two ropes 35 and 36 positioned beneath the driver's seat and shown in Figs. 1 and 6. By pulling one of these ropes, the L slotted member is raised to a position where either of the stub shafts 30^b or 30^c are positioned to slide into the horizontal leg of the L slot; thus, when the brake lever is drawn back, the brake manipulated by the connections from this specific mechanism will be inoperable as the lost motion will be taken up by the horizontal movement of the stub

shaft in the elongated horizontal leg of the L slot. Thus, either of the brakes can be functioned separately or simultaneously according to the whim of the operator. A rugged type of external brakes, such as that shown at 37 in Fig. 1, are used in place of the usual braking mechanism. These brakes are built to withstand the rough usage to which they are subjected.

The particular detail of the lever connections between the brake bands and the actuating links 28 has been omitted for simplicity, as the operation is obvious from the showing in Fig. 1.

The rear radius rods 38 are moved forward with the rear axle mechanism in order to maintain the mechanism rigidly in position.

When running normally, a bucking movement is produced due to the eccentric mounting of the front wheels. With the sudden reversal of the driving mechanism and a sudden braking, the front end of the machine may be reared up, causing the body to rest upon its haunches or upon the drag disk. The vehicle may then be pivoted while in a reared-up position, by braking either of the wheels and the car may again be brought up into a horizontal position by driving forward and suddenly braking both wheels. It is obvious that innumerable antics and gyrations may be effected by the operator in the way of sudden startings, stoppings, whirlings and bucking movements,—all of which may be accentuated by familiarity with the operation of the mechanism.

I claim as my invention:

An amusement device adapted to perform antics such as rearing, bucking and pivoting rapidly in either direction with the manipulation of the control mechanism, consisting of a motor driven vehicle having its rear wheels moved forward to the position of a fulcrum to substantially balance the body when loaded, eccentrically mounted front wheels, separate brakes and brake controls for the respective wheels, and drag means at the rear of the body upon which the body rests and slides when in a reared up position.

GEORGE T. O'MALEY.
